UNITED STATES PATENT OFFICE.

JOHN J. TATUM, OF BALTIMORE, MARYLAND.

DUMP-CAR.

1,235,739.

Specification of Letters Patent.

Patented Aug. 7, 1917.

Application filed December 11, 1915. Serial No. 66,234.

To all whom it may concern:

Be it known that I, JOHN J. TATUM, a citizen of the United States, residing at Baltimore, in the county of Baltimore and State of Maryland, have invented a certain new and useful Improvement in Dump-Cars, of which the following is a full, clear, concise, and exact description, reference being had to the accompanying drawings, forming 10 a part of this specification.

This invention relates to improvements in dump cars.

One of the objects of the invention is to provide improvements whereby the capacity 15 of dump cars of the types now in service may be increased without changing the overall dimensions thereof.

Another object of the invention is to so arrange the hopper doors of dump cars that 20 the cars may be unloaded in quicker time than is now the case without necessarily changing the door opening area of the hoppers.

Another and more specific object of the 25 invention is to provide a novel form of hopper door for dump cars which may be used in place of the ordinary hopper doors now used, which improved hopper door will materially increase the capacity of the car and 30 without increasing the cost.

The invention furthermore consists in the improvements in the parts and devices and in the novel combinations of the parts and devices herein shown, described and claimed.

35 In the drawing forming a part of this specification, Figure 1 is a longitudinal, vertical sectional view of one type of hopper dump car showing my improvement in connection therewith, slightly more than half 40 of the car being illustrated. Fig. 2 is a transverse, sectional view of the car illustrated in Fig. 1 and taken substantially on the line 2—2 of the latter. And Figs. 3 and 4 are views corresponding respectively with 45 Figs. 1 and 2 and illustrating my improvements in connection with another type of car, Fig. 4 being taken on the line 4—4 of Fig. 3.

50 Referring first to Figs. 1 and 2, the improved dump car, as shown, is provided with side walls 10, short, vertical end walls 11, built-up center sill 12, end bottom hopper sheets 13 and outwardly and downwardly inclined hopper bottom sheets 14. Vertical 55 transverse hopper sheets 15 and 16 are also employed, the hoppers being arranged longi-

tudinally of the car and on opposite sides of the center sill, there preferably being four hoppers in all, two on each side.

Referring now more particularly to Fig. 60 2, it will be seen that the hopper designated generally by the reference A is a side dumping hopper and the door opening thereof is adapted to be closed by my improved door B. The improved door B, as shown, 65 comprises a main plate 17 having a right angled, longitudinally extending flange 18 along its upper edge, and triangular shaped end walls or flanges 19—19. Each door B is preferably provided with a pair of hinge 70 butts 20—20 secured to the outer faces thereof along the upper flange 18 and back of the main plate 17, said hinge butts 20 being pivoted to depending brackets 21—21 secured to longitudinally extending angles 22, 75 the latter in turn being riveted to the downwardly extending side walls 10 and side stakes 23 of the car. In order to operate each pair of doors B on each side of the center sill, simultaneously, I have provided a Z bar 80 24 which extends longitudinally of the doors and is secured to the outer sides thereof. The door operating mechanism is connected with the Z bars, each door operating mechanism comprising a relatively long, pivoted, 85 hook shaped link 25, the latter in turn being pivoted to a short link 26, said link 26 being pivoted to another link 27, the latter in turn being pivoted to an integral arm 28 formed on the hub or drum 29, mounted on 90 a longitudinally extending shaft 30 which is mounted in suitable depending brackets 31 secured to the underside of the built-up center sill. As will be understood, the door operating mechanism is the same for each 95 set of doors and is so arranged that when the doors are in closed position, the mechanism is self locked and the shaft 30 relieved of torsion, in a well known manner. I have not shown the means for operating the shaft 100 30, since I do not deem it necessary, it being understood that the same will be operated from a transverse shaft with suitable connections therebetween and the shaft 30.

Referring now to the structure illustrated 105 in Figs. 3 and 4, the dump car illustrated therein is of the so-called W shape type wherein are provided four hoppers A' A', two on each side of the center sill 112, the hoppers A' being arranged in pairs, two at 110 each end and adapted to dump toward the center of the car. Each hopper A' is pro-

vided with an inclined bottom 113 which extends from the end wall 111, longitudinally extending inner and outer hopper sheets 114 and 115, and transversely extending inclined hopper sheets 116 at the center of the car, the latter meeting at the longitudinal center of the car and forming an apex or ridge to thereby divert the coal or other material to the hoppers and prevent bridging of the material.

In this type of cars, I employ similar hopper doors B', the latter being hinged along their upper edges by means of the hinge butts 120 pivoted to brackets 121 secured to a transversely extending angle iron 122, the latter in turn being secured to the under side of the hopper sheet 116. Each set of hopper doors B', at each end of the car, is operated simultaneously, and for this purpose I provide a transversely extending built-up bar 124, the latter having secured thereto at its center beneath the center sill and between the two doors B', an eye bolt 40 to which is pivoted a link 41, the latter in turn being pivoted to a lever arm 42 formed integral with a drum 43 mounted on the cross shaft 44, the latter being mounted in suitable brackets, as will be understood, and operated from the side of the car.

From the preceding description, it will be seen that the improved hopper doors B and B' are substantially of scoop form and that the load capacity of the car is increased by an amount substantially equaling the volume defined by the outlines of the doors B and B'. Inasmuch as there are four of these doors to the car, in the types which I have illustrated, it is apparent that the increased capacity is considerable, and that this increased capacity is obtained without in any way affecting the overall dimensions of the car. Furthermore, this increased capacity is obtained in such a manner that the center of gravity of both the car and the load of the latter is lowered. This minimizes danger of the wheels climbing the rails and permits high speed of the car with safety. It will also be apparent that upon opening the doors B and B', the load is released much quicker than with the ordinary type of flat door since the scoop shape of the doors causes the latter to swing out from under the load near the top of the door openings which is not true of the ordinary hinged flat doors. Furthermore, it will be noted that my improved type of doors may be substituted for the common form of doors; they may be cheaply manufactured; the doors are strong and rigid inasmuch as the triangular shaped end walls 19 serve as strengthening flanges and the corrugations 50, which ex-

tend transversely of the doors, also brace them.

Although I have herein shown and described what I now consider the improved method of carrying out my invention, the same is merely illustrative and it is obvious that changes in the details of construction may be made without departing from the spirit of the invention, and also that the improved doors are adaptable for dump cars of other types than those illustrated herein.

I claim:

1. A hopper car of the character described having a center sill and side walls with longitudinally extending hoppers, each of said hoppers having triangular shaped end hopper sheets and a downwardly and outwardly inclined hopper bottom sheet, and hinged doors for said hoppers, each of said doors comprising a main portion with a longitudinally extending flange substantially at right angles to the main portion and substantially right angled triangular shaped ends, whereby said doors are scoop shaped and adapted to carry a part of the car load and lower the center of gravity of the car, said flange being disposed uppermost and the door being hinged from said flange adjacent the bottom of the side wall of the car, the main portion of each door normally being inclined downwardly and inwardly, the door when swung open having the main portion thereof inclined downwardly and outwardly whereby the door automatically clears itself of the load and the load of the car is discharged outwardly.

2. In a hopper car of the character described having a plurality of hoppers intermediate the trucks, each of said hoppers including a downwardly inclined hopper bottom sheet, and doors for closing each of said hoppers, each of said doors comprising a main portion with a flange at right angles thereto extending longitudinally along the top of the door, said doors being hinged from said flanges, each of said doors having also triangular shaped ends to thereby adapt each door for carrying a part of the load, said doors being arranged to swing about axes parallel to the plane of the main portions thereof, the main portions of said doors being corrugated substantially as specified.

In witness that I claim the foregoing I have hereunto subscribed my name this 6th day of Dec., 1915.

JOHN J. TATUM.
